UNITED STATES PATENT OFFICE.

HIRAM H. SPONENBURG, OF GURNEE, ILLINOIS, ASSIGNOR TO OTTO R. BARNETT, OF CHICAGO, ILLINOIS.

RAIL-ANCHOR.

1,170,940.

Specification of Letters Patent.

Patented Feb. 8, 1916.

Application filed May 2, 1914. Serial No. 835,900.

To all whom it may concern:

Be it known that I, HIRAM H. SPONENBURG, a citizen of the United States, residing at Gurnee, in the county of Lake and State of Illinois, have invented certain new and useful Improvements in Rail-Anchors, of which the following is a specification.

My invention relates to a rail anchor, that is to say, a device for preventing the longitudinal creep of a railroad rail; and the principal object of the invention is to provide a new and improved type of rail anchor which will be simple in construction, light in weight, inexpensive to manufacture and strong, and which will take a firm and reliable hold on the rail which will not be disturbed by vibration, difference in contraction and expansion as between the parts of the device and the rail, due to temperature changes, or to other causes tending to impair the gripping or holding power which is essential to the efficiency of a device of this class.

A further and specific object of the invention is to provide a novel form of rail anchor utilizing spring pressure for effecting and maintaining an intimate clamp of the device on the rail.

A further object is to provide a device in which the parts constituting the rail clamp have large areas of contact with the rail and with each other.

A further object is to provide a device, one member of which is wedged against the web of the rail in such manner that the holding power of the device under all conditions will be very good.

A further object of the invention is to provide a device, the grip of which on the rail will not be affected by a retrograde movement of the rail, that is, a movement contrary to the normal creep.

The invention is illustrated, in certain preferred embodiments, in the accompanying drawings wherein—

Figure 1 illustrates, in elevation, a rail anchor, constructed in accordance with the invention, applied to a rail which is shown in cross section; Fig. 2, a plan view of the parts shown in Fig. 1; Fig. 3, a sectional view on line 3—3 of Fig. 2; Fig. 4, a sectional view on line 4—4 of Fig. 1; Fig. 5, a view, in perspective, of the spring wedge constituting one of the elements of the de-

vice shown in the preceding figures; and Figs. 6, 7 and 8, views corresponding respectively to Figs. 1, 2 and 5 illustrating a modified form of the invention.

Like characters of reference designate like parts in the several figures of the drawings.

In the drawings, 10 designates a railroad rail and 11 one of the cross ties on which the rail is supported.

Referring first to Figs. 1 to 5 inclusive, the rail anchor herein shown is made up of two elements, a yoke 12 which extends around the base flange of the rail, being formed at opposite ends with jaws 13 and 14, and a wedge member 15 which intervenes between the jaw 14 of the yoke and the rail 10. One of these elements, preferably the yoke 12, is formed with a tie abutting flange 16, or other suitable means, for giving the device a stationary position on the road-bed as against a forward creeping tendency of the rail.

The element 15 has preferably a certain amount of elasticity. In this particular embodiment of the invention it consists of a steel plate which is bowed up from the base flange of the rail, Fig. 5 being a view of the under side of the element. It is preferably formed with an upturned rim 17 by means of which it may be driven between the base flange of the rail and the jaw 14. The element is in the form of a wedge, being wider at its rear edge than at its forward edge, and is preferably formed with a depending flange 18 which overhangs, but without touching, the vertical edge of the base of the rail. The flange 18 is by preference wedge-shaped as shown and formed with an inturned tooth 19.

The device, constructed as above described, is applied to the rail by first slipping the yoke over the rail base with its tie abutting flange against the tie 11, and then driving the wedge in between the jaw 14 of the yoke and the base of the rail. This compresses or flattens out the member 15 and at the same time wedges it between the jaw and the upstanding web of the rail. These engagements, which put the spring member 15 under tension, serve to preserve the intimacy of the hold of the device on the rail under varying conditions particularly as against the tendency of the device to become loose on the rail due to unequal expansion and

contraction of the rail and the anchor parts and as against the loosening tendency due to vibration. The tooth 19 prevents any retrograde movement of the wedge. If desired, the tooth may be set into the rail, after the anchor has been adjusted to its operative position, by hammering. It will be observed that the tie abutting plate 16 holds the end of the yoke having the jaw 13 out of contact with the tie 11 so that a forward creep rocks the anchor on the rail so as to increase all of the holding stresses.

In Figs. 6 to 8 inclusive, I have shown a rail anchor similar to that shown in the preceding figures except for a modification in the form of the wedging member. The device consists of a yoke 20, having a tie abutting flange 21 and jaws 22 and 23, this part of the device being substantially the same as the corresponding element in the other anchor. The other member consists of a bowed elastic plate 24 of less width than the base flange which it engages, formed on its outer edge with a depending wedge-shaped flange 25. When the member 24 is driven in between the jaw 23 and the base of the rail it is compressed or flattened, as in the other construction, but does not bear against the upstanding web of the rail. The wedging action is produced by the contour of the flange or rib 25. The latter may be provided at its rear end with a tooth 26.

While I have described my invention as embodied in certain preferred constructions, modifications might be made without departure from the principles of the invention. Therefore I do not wish to be understood as limiting the invention to the particular constructions, arrangements and devices shown and described except so far as these limitations are specifically set forth in certain of the claims herein.

I claim:

1. A rail anchor comprising two rail gripping elements, one of which is formed with means for giving the device a fixed position in the road-bed as against the tendency of the rail to creep, and one of which comprises a spring element which bears upon the upper side of the base flange of the rail, and is put under tension by the other element.

2. A rail anchor comprising two rail gripping elements, one of which is formed with means for giving the device a fixed position in the road-bed as against the tendency of the rail to creep, and one of which comprises a spring element which bears upon the upper side of the base flange of the rail and against the upstanding web thereof and is put under tension by the other element.

3. A rail anchor comprising two rail gripping elements, one of which is formed with a tie abutting flange, one of which

comprises an element which is wedged between the other element and the upstanding web of the rail.

4. A rail anchor comprising two rail gripping elements, one of which is formed with means for giving the device a fixed position in the road-bed as against the tendency of the rail to creep, one of which comprises a spring member which bears upon the top of the base flange of the rail, and the other a yoke which embraces said spring member and the rail base.

5. A rail anchor comprising two rail gripping elements, one of which is formed with means for giving the device a fixed position in the road-bed as against the tendency of the rail to creep, one of which consists of a yoke which extends around the base of the rail, and the other comprises a spring member which is wedged between said yoke and the upstanding web of the rail.

6. A rail anchor comprising two rail gripping elements, one of which is formed with a tie abutting flange, one of which consists of a yoke which extends around the base of the rail, and the other comprises a member which is wedged between said yoke and the upstanding web of the rail.

7. A rail anchor comprising two rail gripping elements, one of which is formed with means for giving the device a fixed position in the road-bed as against the tendency of the rail to creep, one of which comprises a spring member bearing against the upstanding web of the rail and provided with a depending flange which overhangs the outer edge of the rail base, and the other, a yoke which embraces said rail base and said spring member.

8. A rail anchor comprising two rail gripping elements, one of which is formed with a tie abutting flange, one of which consists of a yoke extending around the base of the rail, and the other being adapted to bear against the upstanding web of the rail and being formed with a depending flange overhanging the outer edge of the rail base.

9. A rail anchor comprising two rail gripping elements, one of which is formed with means for giving the device a fixed position in the road-bed as against the tendency of the rail to creep, one consisting of a yoke embracing the base of the rail, and the other being elastic and adapted to intervene between said yoke and a flat surface of the base of said rail and being formed with a flange extending between the outer edge of the rail base and the yoke, which flange is provided with a tooth arranged to bite into the rail base.

10. A rail anchor comprising two rail gripping elements, one of which is formed with means for giving the device a fixed position in the road-bed as against the tendency of

- the rail to creep, one consisting of a yoke embracing the base of the rail, and the other being elastic and adapted to intervene between said yoke and the base of the rail and formed with a flange extending between the outer edge of the rail base and the yoke.
11. A rail anchor comprising a yoke and a spring wedge which intervenes between the yoke and the upper surface of the base of the rail.
12. A rail anchor comprising a yoke and a spring wedge which intervenes between the yoke and the upper surface of the base of the rail, one of said elements being provided with a tie abutting flange.
13. A rail anchor comprising a yoke and a spring wedge which intervenes between the yoke and the upstanding web of the rail, one of said elements being formed with a tie abutting flange.
14. A rail anchor comprising a yoke and an elastic wedge which intervenes between the yoke and the upstanding web of the rail, one of said elements being formed with a tie abutting flange.
15. A rail anchor comprising a yoke formed with a tie abutting flange and a wedge member adapted to be driven between the yoke and the upstanding web of the rail.
16. A rail anchor comprising a yoke formed with a tie abutting flange and a wedge member adapted to be driven between the yoke and the upstanding web of the rail formed with a depending flange which intervenes between the yoke and the outer edge of the rail base.
17. A rail anchor comprising a yoke formed with a tie abutting flange and a spring wedge member adapted to be driven between the yoke and the upstanding web of the rail formed with a depending flange which intervenes between the yoke and the outer edge of the rail base.
18. A rail anchor comprising a yoke formed with a tie abutting flange and a spring wedge member adapted to be driven between the yoke and the upstanding web of the rail formed with a depending flange which intervenes between the yoke and the outer edge of the rail base, said last named flange being formed with a tooth, for the purpose described.
19. A rail anchor comprising a yoke formed at one end with a jaw adapted to fit one edge of the base flange of the rail, at the other end with a larger jaw extending around the opposite edge of the rail base, and with a tie abutting flange which holds
- said first named jaw out of contact with the tie against which the tie abutting flange bears; and a spring wedge member adapted to be driven between the larger jaw and the base of the rail, the inner edge of which engages the upstanding web of the rail and the outer edge being formed with a depending rib provided with a tooth.
20. A rail anchor comprising rail gripping elements, one provided with a tie abutting member and one comprising a bowed spring which bears against a flat surface of the rail, is flexed when the anchor is in operative position and is provided with a tooth which bites into the rail base.
21. A rail anchor comprising rail gripping elements, one provided with a tie abutting member and one comprising a bowed spring which bears against a flat surface of the rail, is flexed when the anchor is in operative position and is provided with a tooth which bites into the edge of said rail base.
22. A rail anchor comprising a wedge-shaped bowed spring adapted to bear against a flat surface of the rail, and a yoke embracing the rail base and spring so as to put the latter under stress, one of said elements being provided with a tie abutting member.
23. A rail anchor comprising a wedge-shaped bowed spring adapted to bear against a flat surface of the rail, and a yoke embracing the rail base and spring so as to put the latter under stress, one of said elements being provided with a tie abutting member and said spring being formed with a tooth which bites into the rail.
24. A rail anchor comprising a wedge-shaped bowed spring adapted to bear against a flat surface of the rail, and a yoke formed with a tie abutting member, which yoke embraces the rail base and spring so as to put the latter under stress.
25. A rail anchor comprising a bowed spring adapted to bear against a flat surface of the base of the rail, and a yoke which embraces the rail base and spring so as to put the latter under stress, one of said elements being formed with a tie abutting member and the spring being formed with a wedge-shaped flange which intervenes between the edge of the base flange of the rail and said yoke.
